LOCOMOTIVE

Chester A. Siegel, Newark, and John P. Neff, East Orange, N. J., assignors to American Arch Company, New York, N. Y., a Corporation of Delaware

Application March 14, 1930. Serial No. 435,704

3 Claims. (Cl. 122—68)

This invention relates to locomotives, and particularly to locomotive fire box and arch constructions.

One of the primary objects of the invention is to simplify and improve locomotive fire box arches and the support thereof, and at the same time to promote water circulation in the water leg of the fire box and to increase the evaporative surface in a fire box of given size.

10 Other important objects of the invention involve: the provision of increased flexibility in the fire box side sheets and the elimination of wear on the side sheets by the refractory arch bricks, whereby longer life for the fire box is attained, along with greater safety; the elimination of the necessity for relatively long side brick and of the necessity for different sizes of side brick in the same fire box; the making feasible the employment of a single size and pattern of side brick in 20 all cases, and of middle brick in many cases, or even making possible the use of a single form of brick for the whole arch, whereby the advantage of a large decrease in the number of brick sizes and patterns to be carried in stock is attained; the obviation, in locomotive fire boxes employing middle water legs, of the usual necessity for arch tubes between the middle and side water legs, especially in wide fire boxes; and, in general, the improvement and simplification of the fire box 25 and arch construction as a whole, and the reduction of costs, especially for maintenance and repair.

That the full purport of the foregoing general statement of objects and advantages may be realized, it should be understood that, in constructions heretofore known in the art, it has generally been necessary not only to employ different sizes and shapes for middle and side bricks, respectively, but also different sizes of side brick 40 in the same fire box owing to the difference in width between the side sheets at the upper rear end and the lower front end of the arch, which presents a very serious problem in the long fire boxes which are now generally coming into use.

45 Furthermore, in large fire boxes, and especially in very long fire boxes, the side sheets are subjected to serious strains from expansion and contraction, and owing to the length of the water legs the circulation in the lower rear corners thereof is apt to be sluggish.

Specifically, therefore, the present invention involves primarily the overcoming of the difficulties heretofore encountered, by the provision of a comparatively simple device which serves a five-fold purpose, and from which other inci-

dental advantages result. In the preferred form, the invention involves the provision in each side sheet of the fire box, of a channel member which may be secured to or formed integrally with the side sheet, such member being elongated substantially lengthwise of the side sheet, being preferably substantially U-shaped in cross section deepening toward the front of the fire box, and having a forwardly extending throat member which is adapted to be secured into the throat sheet of the fire box. The five chief purposes served by this construction are: to provide increased evaporative surface, to accommodate expansion and contraction of the side sheet, to increase the circulation in the side water leg, to provide a simple and stable support for the side brick of the arch and prevent wear of such brick against the side sheet, and to make possible the employment of a refractory arch of uniform width from the lower front end to the upper rear end and avoid the necessity for different lengths of brick.

How the foregoing objects and advantages are attained by our invention, together with such other advantages as are incident to the invention or will occur to those skilled in the art, will be clear from the following description, taken together with the accompanying drawings, in which drawings

Figure 1 is a vertical longitudinal mid-section thru the fire box of a locomotive, taken on the line 1—1 of Fig. 2, embodying our improvements;

Figure 2 is a vertical transverse section taken on the line 2—2 of Fig. 1;

Figure 3 is a longitudinal section thru the chief structural element of the invention, taken on the line 3—3 of Fig. 1 and showing the connection of the element to the side and throat sheets of the fire box;

Figure 4 is a fragmentary enlarged sectional view, in general similar to Fig. 2, of an arch and fire box structure showing our invention applied to a modified form of fire box; and

Figures 5, 6 and 7 are views similar to Fig. 4 illustrating still other modifications in which our invention is applied.

By reference first to Figs. 1, 2 and 3, it will be seen that we have illustrated a locomotive fire box construction having front and rear water legs 2, 3, formed, respectively, by outside and inside sheets 4, 5 and 6, 7; side water legs 8, 8, formed by the outside and inside side sheets 9 and 10; water and steam space 11, defined by the crown sheet 12 and roof sheet 13; flue sheet 14, in which the flues 15 are secured; the usual

mud ring 16; and fire door opening 17. In this fire box, as is now frequently the practice, are placed two inner or middle water legs 18, 18, which open upwardly into the space 11 above the crown sheet 12, and which have bulbous portions 19 inclined downwardly and forwardly with a connection 20 to the throat sheet 5.

Ordinarily, in such a fire box, the middle bricks 21 of the arch are supported between the two bulbs 19 of the middle water legs, and the side arch bricks 22 rest at their inner ends on the bulbs 19 and extend outwardly and upwardly to rest at their outer ends directly against the side sheets 10. Owing to the inclination of the arch, as seen in Fig. 1, and the inclination of the sheet 10 as seen in Fig. 2, the width to be spanned by the side brick is greater at the front of the arch than at the rear of the arch. This ordinarily necessitates either a steep angle of inclination of the side bricks at the back of the arch and a very flat angle at the front end, or else the employment, particularly in long fire boxes, of two or three different sizes or lengths of side brick.

By our invention, the brick-supporting water-circulating, expansion member or channel 23, which, as shown in Figs. 2 and 3, is welded in as a part of the inside side sheet 10, compensates for the difference in distance between the side sheets 30 at the lower front end of the arch and at the upper rear end of the arch, so that a straight-line brick contacting surface 24, exactly parallel with the bulbous portion 19 of the inner water leg, is provided. It will thus be seen, as in Fig. 2, that the side brick 22 may all be of the same shape and size, and all lie at the same angle, in this case being placed horizontally from end to end of the brick. In fact, in the construction shown in Fig. 2, if our invention were not employed, the side brick would have to be of a prohibitive span, or else supplemental supporting arch tubes would have to be employed between the middle water legs and the side sheets, and in either event the brick would have to be set at different angles or bricks of different lengths would have to be employed. The invention eliminates all of these difficulties, and as will be seen from Fig. 2 makes it possible even to employ a single form of brick throughout the entire arch.

From Figures 1, 2 and 3, it will be further apparent that the simple U-shaped channel device, or inwardly-bowed side sheet construction, which we have used to attain these results also serves to provide for expansion and contraction of the side sheets without breakage or cracking thereof, to provide additional evaporating surface, and to effect a circulation of water, by means of the throat 23a, which is connected to the water leg 2 thru the throat sheet 5, back into the side water leg, the cross-sectional area of the passage thru the channel member being naturally gradually reduced toward the rear end. It may be here mentioned that the connection of the member 23 to the sheets 5 and 10 may conveniently be made, as here shown, by swaging the end of the throat piece 23a into sheet 5 and welding the member 23 into the side sheet 10, thus giving a very stable and firm support.

That the invention is very flexible in its arrangement, that is, capable of application to varying types of fire boxes and arch brick arrangement, will be evident from Figs. 2, 4, 5, 6 and 7. In Fig. 2, as heretofore shown, the invention cooperates with a pair of middle water legs,

to support an arch made up of a single type of brick throughout, each of which has a socketed end for firm seating, and a bevelled end for slight adjusting variations to fit the spacing between the supporting members.

In the arrangement shown in Fig. 4, the internal water legs are spaced farther apart, and while the side brick employed are all of one form and length, the middle brick is made of slightly larger span, all the bricks being socketed at each end. In this case also, a good firm seating of the brick 22a is provided on the curved surface 24 of the member 23, all wear on the side sheet being eliminated, the elongated middle brick 21a seating firmly between the two internal water legs 18.

In Fig. 5 the invention is shown as applied to a fire box in which internal water legs are eliminated, but three arch tubes 25 are used. In this arrangement, as in the arrangement of Fig. 2, the entire arch is made up of one type of brick, which in this instance gives a flat arch, the brick 22b being reversible, and so cut at their ends as to provide for different spacings of tubes and side sheets.

In Fig. 6, it will be seen that the supporting members 23, with their rounded seats 24, provide a strong and stable support for an entirely refractory arch structure, which for purposes of safety and strength is made up of substantially upwardly curved brick 22c, interlocking with one another as at the point 26.

In the modification shown in Fig. 7 it will be seen that the invention cooperates with the widely spaced internal water legs 18a and the central arch tube 25a to provide for the use of a single type of brick throughout the arch.

In any of the arrangements, it will be seen that the invention accomplishes in a very simple manner the five main purposes hereinbefore stated, and in general materially simplifies and improves the arch and fire box structure taken as a whole, and is capable of cutting down to a minimum the number of brick styles and sizes required to be kept in stock. While we have not illustrated them, it will, of course, be understood that the usual staybolts are preferably employed in the water-legs, and also in the elements 23.

What we claim is:

1. A locomotive fire-box construction having side wall water legs spaced from each other different distances as between an upper rear portion of the box and a lower forward portion thereof, an arch brick supporting structure intermediate said side water legs and extended generally from an upper rear portion of the box forwardly and downwardly to a lower forward portion thereof, an arch brick supporting element in the form of a water leg communicating with a side water leg, extended similarly to said structure from an upper rear portion of the box forwardly and downwardly to a lower forward portion thereof and varying in width to present an inner arch brick supporting edge generally parallel to said structure, and refractory arch bricks having opposite ends supported on said structure and said element, whereby bricks of uniform dimensions transversely of the fire-box may be employed substantially throughout the length of the refractory arch.

2. A locomotive fire-box construction having side wall water legs spaced from each other different distances as between an upper rear portion of the box and a lower forward portion thereof, an arch brick supporting structure intermediate said side water legs and extended

generally from an upper rear portion of the box forwardly and downwardly to a lower forward portion thereof, an arch brick supporting element in the form of a water leg communicating with a side water leg, extended similarly to said structure from an upper rear portion of the box forwardly and downwardly to a lower forward portion thereof and varying in width to present an inner arch brick supporting edge generally parallel to said structure, and refractory arch bricks having opposite ends supported on said structure and said element, whereby bricks of uniform dimensions transversely of the fire-box may be employed substantially throughout the length of the refractory arch, said arch brick supporting structure comprising a water circulating element.

3. A locomotive fire-box construction having side wall water legs spaced from each other different distances as between an upper rear portion of the box and a lower forward portion thereof, an arch brick supporting structure intermediate said side water legs and extended generally from an upper rear portion of the box forwardly and downwardly to a lower forward portion thereof, an arch brick supporting element supported by and secured to a side water leg, extended similarly to said structure from an upper rear portion of the box forwardly and downwardly to a lower forward portion thereof and varying in width to present an inner arch brick supporting edge generally parallel to said structure, and refractory arch bricks having opposite ends supported on said structure and said element, whereby bricks of uniform dimensions transversely of the fire-box may be employed substantially throughout the length of the refractory arch.
